Primary Examiner — Karen S Acker(74) Attorney, Agent, or Firm — Barlow, Josephs & Holmes, Ltd.(57) CLAIM

The ornamental design for a flat front fireplace insert, as shown and described.

DESCRIPTION

FIG. 1 is a perspective view of the flat front fireplace insert in accordance with the present invention;

FIG. 2 is a front view thereof;

FIG. 3 is a back view thereof;

FIG. 4 is a top view thereof;

FIG. 5 is a bottom view thereof; and,

FIG. 6 is a right side view thereof, the right and left sides being mirror images.

The broken lines in the drawings represent environmental subject matter that forms no part of the claim.
